UNITED STATES PATENT OFFICE

148,916

DESIGN FOR A TABLE TOP

Donald H. Dickerman, Newport Beach, Calif., and Frank H. Coburn, Sea Cliff, N. Y.

Application May 15, 1946, Serial No. 129,727

Term of patent 14 years

(Cl. D33—14)

To all whom it may concern:

Be it known that we, Donald H. Dickerman, a citizen of the United States, resident of Newport Beach, in the county of Orange and State of California, and Frank H. Coburn, resident of Sea Cliff, in the county of Nassau and State of New York, have invented a new, original, and ornamental Design for a Table Top, of which the following is a specification, reference being had to the accompanying drawings, forming part thereof.

In the drawings:

Fig. 1 is a top plan view taken from above the table top showing our new design.

Fig. 2 is a view of the table top taken from approximately 45° of the horizontal plane from the upper right hand side of Fig. 1.

The side of the table top not shown in the drawings is undecorated.

The essential feature of the design shown in the drawings is the decorative effect achieved in the edge of the top.

We claim:

The ornamental design for a table top, substantially as shown and described.

DONALD H. DICKERMAN.
FRANK H. COBURN.
